UNITED STATES PATENT OFFICE

JOHN H. FISCHER, OF NEW YORK, N. Y., ASSIGNOR TO EAGLE PENCIL COMPANY, OF NEW YORK, N. Y., A CORPORATION OF DELAWARE

DESIGN FOR A COMPASS OR SIMILAR ARTICLE

Application filed March 12, 1929. Serial No. 30,446. Term of patent 7 years.

To all whom it may concern:

Be it known that I, JOHN H. FISCHER, a citizen of the United States of America, residing at New York, in the county of Queens and State of New York, have invented a new, original, and ornamental Design for a Compass or Similar Article, of which the following is a specification, reference being had to the accompanying drawings, forming part thereof, in which—

Fig. 1 is an elevation of the article showing my new design, it being understood

that the ornamentation shown is continued throughout the legs of the compass.

Fig. 2 is a fragmentary enlarged detail view of the ornamentation.

I claim:

The ornamental design for a compass or similar article, substantially as shown and described.

In testimony whereof I hereby affix my signature.

JOHN H. FISCHER.
